ABSTRACT OF THE DISCLOSURE

As new compounds suitable as fungicidal agents, there are provided isothiazole derivatives of the formulae:

and

wherein

R₁ represents alkylene of 1-4 carbon atoms;
R₂ represents alkyl of 1-4 carbon atoms, or X_n-phenyl wherein n is an integer of 1-3 and X is hydrogen, hydroxy, alkyl of 1-4 carbon atoms, or halogen, or 2X represent methylenedioxy; and
R₃ represents alkyl of 1-4 carbon atoms.

This invention relates to derivatives of 4-cyano-isothiazoles, and in particular to those derivatives having fungicidal properties.

An object of this invention, is, therefore, to provide novel chemical compounds and, concomitantly, intermediates, by-products, and processes relating to the production of such compounds.

2

comprises isomeric compounds of Formulae Ia and/or Ib:

and

wherein

R₁ represents alkylene of 1-4 carbon atoms;
R₂ represents alkyl of 1-4 carbon atoms; phenyl; or phenyl substituted by 1-3 hydroxy or alkyl groups, halogen atoms, or methylenedioxy; and
R₃ represents alkyl of 1-4 carbon atoms.

These fungicidal agents can be incorporated with conventional carriers and/or fillers, and, if desired, additional conventional fungicides.

The activity of the novel compounds was determined in the spore germination test and in the infection test. The LD₅₀ and LD₉₅ were determined, i.e., that amount of active agent (measured in mg./100 cm.²) which prevents, to an extent of 50% and 95%, respectively, the germination of the fungus spores in the spore germination test, and the growth of the fungus on the leaf surface in the infection test.

The novel compounds were compared with the known highly effective fungicide N-trichloromethylthio-tetrahydrophthalimide, as a standard. In the spore germination test on *Venturia* the novel fungicides 3-acetylthio-methylthio-5-methylthio-4-cyano-isothiazole and 5-acetylthio-methylthio-3-methylthio-4-cyano-isothiazole are two to three times more effective than the standard compound, whereas approximately the same activity is observed when using these agents in the spore germination test on *Alternaria*. Similar data was obtained in the infection-preventing experiment in the leaf spraying test on *Plasmopara viticola* wherein approximately the same LD₉₅ is obtained as in using N-trichloromethylthio-tetrahydrophthalimide. The following table presents a summary of the data:

TABLE

	Spore germination test on	
	<i>Venturia inaequalis</i>	<i>Alternaria spec.</i>
N-trichloromethylthio-tetrahydrophthalimide (standard)-----	1	1
3-acetylthiomethylthio-5-methylthio-4-cyano-isothiazole-----	2	1
5-acetylthiomethylthio-3-methylthio-4-cyano-isothiazole-----	3	1.4

Another object is to provide novel compositions and methods for effecting fungicidal activity.

Upon further study of the specification and claims, other objects and advantages of the present invention will become apparent.

To attain these objects, it was discovered that a group of 4-cyano-isothiazoles possess excellent fungicidal properties, being particularly effective on the known fungi *Venturia inaequalis*, the cause of apple scab, on *Alternaria spec.*, the leaf spot causing fungus, and on *Plasmopara viticola*, the cause of false grapevine mildew. The group of fungicidal 4-cyano-isothiazoles of this invention

55 In view of the actual tests, it is reasonable to expect that the fungicidal agents will also exhibit a finite fungicidal activity with fungi of the following genus: *Alternaria*, *Botrytis*, *Bremia*, *Cercospora*, *Cladosporium*, *Colletotrichum*, *Helminthosporium*, *Monilia*, *Peronospora*, *Piricularia*, *Phytophthora*, *Septoria*, *Sclerotinia*, *Venturia*. Referring to the novel compounds of Formulae Ia and

Ib, R₁ represents methylene, ethylene, as well as the straight-chain or branched propylene and butylene residues.

R₂ is either an alkyl residue of 1-4 carbon atoms, i.e., methyl, ethyl, n- or isopropyl, or n-, sec-, or tert- butyl;

duced when anhydrous solvents are employed in all instances. In this case, it is advantageous first to react the starting material with a 2-halogenoalkylacyl sulfide and thereafter with an alkylating agent.

Conversely, the isomer of the product produced on an anhydrous basis, is selectively obtained when the starting compound is one of Formula IIa or IIb wherein

and if this substituent R_3 has previously been obtained by alkylation of the basic 4-cyano-isothiazole in the presence of water. The resultant salt of the alkylthio-mercapto-4-cyano-isothiazole (IIa or IIb) is preferably first isolated from the aqueous solution and then reacted with an α -halogenoalkylacyl sulfide, this later step being preferably conducted in an anhydrous organic solvent. It is apparent, therefore, that the solvent present during the introduction of the alkyl group R_3 is an important factor in determining which one of the isomeric compounds is obtained.

The reaction temperatures for these reactions generally range between 5° C. and the boiling point of the solvent employed. Normally, about 1/2 to 5 hours are required for conducting the reaction. The isolation and the working up of the novel compounds are conducted in a conventional manner.

For conducting a separate alkylation step, all processes can be employed which are conventional for the alkylation of mercaptides. Particularly suitable reactions are those with alkyl sulfates, alkyl halogenides, and arylsulfonic acid alkyl esters, and especially high yields are obtained when using dimethyl sulfate, methyl bromide, and methyl iodide. The reaction conditions are the same as those described in the literature for these reactions, with respect to the solvent employed, the reaction temperatures, and the reaction times. Pertinent literature is found, for example, in Houben-Weyl, Methoden der organischen Chemie, Volume IX, pages 103-113 (1955).

The isothiazoles of this invention can be beneficially combined with other fungicides, such as, among others:

Copper-containing fungicides, e.g., cuprous oxide, copper oxychloride, copper sulfate, basic copper carbonate, copper zinc chromate, boreaux mixture (mixture of copper sulfate and hydrated lime), copper naphthenate, copper - 8 - hydroxyquinolinate; sulfur-containing fungicides, e.g., wetting sulfur, polysulfides, lime-sulfur mixtures (aqueous solutions of calcium polysulfides and calcium thiosulfate); mercury-containing fungicides, e.g., mercuric chloride, phenylmercuric acetate, benzoate and chloride, ethylmercuric acetate and chloride, 2-methoxyethylmercuric chloride, silicate and phosphate, (3-chloromethoxypropyl)-mercuric acetate, ethylmercuric-2,3-dihydroxypropyl mercaptide, N-(ethylmercuri)-p-tolulsulfonic acid anilide, N-(methylmercuri)-, N-(ethylmercuri)- and N-(phenylmercuri)-1,4,5,6,7,7-hexachlorobicyclo[2.2.1]hept - 5-ene-2,3-di-carboximide, S-(ethylmercuri)-thiosalicylic acid sodium salt, methylmercuri-8-hydroxyquinolinate, methylmercuridicyandiamide, phenylmercuriurea, phenylmercuritriethanolammonium lactate, phenylmercurimonoethanolammonium acetate; tin-containing fungicides, e.g., triphenyltin hydroxide and acetate; thiocarbamates, e.g., the Na-, K-, NH₄-, Zn-, Fe- and Mn-salts of monomethyldithio-, dimethyldithio- and ethylene-bis-dithio carbamic acids; thiurams, e.g., tetramethylthiuram disulfide, polyethylenethiuram disulfide; 2-mercaptopbenzothiazol and its salts; pentachlorophenol; chloronitrobenzenes, e.g., pentachloronitrobenzene, 2,3,5,6-tetrachloronitrobenzene, trichlorodinitro- and trichlorotrinitrobenzenes; 1-thiocyanato-2,4-dinitrobenzene; hexachlorobenzene; 2-sec.butyl-4,6-dinitrophenyl-3'-methyl-2'-butenoate; 7 - methyl-1,3-dithiolo[4,5-b]-chinoxalin-2-on; N,N - dimethyl-N'-phenyl-N'-(dichlorofluoromethylthio)-sulfamide; quinone derivatives, e.g., tetrachloro-p-benzoquinone, 2,3-dichloro-1,4-naphthoquinone, 2,3-dicyano-1,4 - dithiaanthraquinone; N-trichloromethylthio-1,2,3,6-tetrahydrophthalimide, N - trichloromethylthio-phthalimide,

ide, N - (1,1,2,2-tetrachloroethylthio)-1,2,3,6-tetrahydrophthalimide; 2,4 - dinitro-6-(α -methylheptyl)-phenyl crotonate; N-dodecylguanidine acetate; 3,5-dimethyl-1,3,5-2H - tetrahydro - thiadiazine-2-thione; 2,4-dichloro-6-(2-chloroanilino) - 1,3,5-triazine; 5-Amino-1-(bis-dimethylamino-phosphinyl)-3-phenyl-1,2,4-triazole; as well as antibiotics, e.g., tetracycline, chlorotetracycline, hydroxytetraacycline, streptomycins, cycloheximide, celloxydine (acetyl-enedicarboxamide); or 2,6-dichloro-3,5-dicyano-4-phenylpyridine.

The isothiazoles of this invention can be incorporated in all forms of compositions suitable for fungicidal applications, and contain generally about 1 to 95% of the active agent. Adding conventional carriers and/or fillers, there can be produced, for example, sprayable or atomizable agents. Additives such as dressing agents for the preservation of seed; dispersing agents and/or wetting agents can be added. When using the appropriate additives, it is also possible to produce solutions or emulsions of the novel substances, which can, for example, be atomized as aerosols.

More specifically, the agents can be incorporated with pulverulent solids to form sprayable powders or dusting compositions. They also can be incorporated with surface active agents and thickening agents to form sprayable dispersions. Additives and fillers used in this connection are the conventional ones, such as, for example, bole, kaolin, bentonite, ground shale, talc, chalk, dolomite, or kieselguhr, if solid preparations are concerned. For liquid formulations, xylene, solvent naphtha, petroleum, acetone, cyclohexane, dimethyl formamide, or aliphatic alcohols are preferably used as solvents. The emulsion concentrates thus prepared can be marketed as such. Prior to use, the emulsion concentrates are diluted with water in the usual manner. Due to the low solubility of the active agents in organic solvents, it is, however, preferable to formulate them as aqueous dispersions. As organic thickening agents for such dispersions, the following can, e.g., be used: methyl, ethyl, carboxymethyl and hydroxyethyl cellulose, tragacanth, dextrines, alginic acids and their salts, polyvinyl alcohol. Typical inorganic thickening agents are bentonite, attaclay and hectorite. As surface active agents there can be used all wetting and dispersing agents, which are usually applied in pesticides, preferably in an amount of about 0.01 to 1% calculated on the basis of the preparation form for use. Suitable wetting and/or dispersing agents are alkyl benzene sulfonates, alkyl naphthalene sulfonates, polyoxyethylene esters of fatty and resinic acids, alkyl phenol polyglycol ethers.

The compounds being employed as fungicides in a pest control program are generally applied to the locus subject to infestation in a quantity per hectare of about 1 to 50 kg.; preferably about 2.5 to 25 kg. More or less active ingredient can be used in dependence on the vegetation involved.

Without further elaboration, it is believed that one skilled in the art can, using the preceding description, utilize the present invention to its fullest extent. The following preferred specific embodiments are, therefore, to be construed as merely illustrative, and not limitative.

(A) PREPARATION OF THE ACTIVE AGENTS

Example 1

At room temperature, 12.4 g. chloromethyl acetyl sulfide, dissolved in 10 ml. ethanol, are added to 21.8 g. of the disodium salt of 3,5-dimercapto-4-cyano-isothiazole, suspended in 300 ml. absolute ethanol. After the entire amount has been added dropwise, the reaction mixture is agitated for 1-2 hours at 60° C. Thereafter, 14.2 g. methyl iodide, dissolved in 20 ml. ethanol, are added. The mixture is additionally agitated for another hour, cooled at 20° C., and then the reaction product and the precipitated inorganic salts are vacuum-filtered. The residue is leached with 150 ml. boiling ethanol and vacuum-filtered; the ethanol solution is then concentrated to half its previous amount.

The compound 3-acetylthio-methylthio-5-methylthio-4-cyanoisothiazole which precipitates is vacuum filtered.

Yield: 12.3 g.; M.P. 121-123° C.

By analogy, 3-benzoylthio-methylthio-5-methylthio-4-cyano-isothiazole is prepared; M.P. 114-115° C.

Example 2

Under stirring, 12.4 g. chloromethyl acetyl sulfide, dissolved in 10 ml. ethanol, are added dropwise to 21.8 g. of the disodium salt of 3,5-dimercapto-4-cyano-isothiazole, suspended in 300 ml. absolute ethanol. After two hours of agitation at 60° C., 12.6 g. dimethyl sulfate, dissolved in 20 ml. ethanol, are added dropwise. The reaction mixture is stirred for another two hours at 60° C., then cooled to 20° C., and vacuum-filtered. The residue is extracted with 150 ml. boiling ethanol and again vacuum-filtered. The ethanol solution is treated with activated charcoal and concentrated.

Yield: 5.5 g. of 3-acetylthio-methylthio-5-methylthio-4-cyano isothiazole; M.P. 120-122° C.

Example 3

11.3 g. of the potassium salt of 3-mercaptop-5-methylthio-4-cyano-isothiazole are dissolved in 200 ml. ethanol and mixed, under stirring, with 6.2 g chloromethyl acetyl sulfide. Thereafter, the reaction mixture is heated for one hour to 60-70° C., then cooled to 20° C., and the reaction product is precipitated by the careful dropwise addition of water. The 3-acetylthio-methylthio-5-methylthio-4-cyano-isothiazole is vacuum-filtered and recrystallized from 30 ethanol.

Yield: 5.0 g.; M.P. 119-121° C.

Example 4

21.8 g. of the disodium salt of 3,5-dimercapto-4-cyanoisothiazole are dissolved in 300 ml. water and mixed, at 5-10° C. under stirring, within 10 minutes, with 14.2 g. methyl iodide. The reaction mixture is then stirred for another 1½ hours at 5-10° C. and vacuum-filtered from the precipitated 3,5-dimethylthio-4-cyano-isothiazole, the latter being obtained as a by-product. The filtrate is concentrated to dryness, the residue is suspended in 150 ml. ethanol, and within 10 minutes, at 60° C., 11.2 g. chloromethyl acetyl sulfide are added dropwise to the suspension. After the addition is terminated, the reaction mixture is stirred for another hour at 60° C. Then, the inorganic residue is vacuum-filtered, and the mother liquor is concentrated to one-third its volume. The precipitated 5-acetylthio - methylthio - 3 - methylthio - 4 - cyano - isothiazole is vacuum-filtered and recrystallized from ethanol, with the addition of charcoal.

Yield: 5.3 g.; M.P. 70-71° C.

Here it is to be noted that the isomer produced by Examples 1-3 has the same melting point of 121° C. ± 2 °, whereas the isomer of Example 4 has a melting point of 70-71° C. This proves definitely that the two isomers can be produced, depending on the process employed. However, there is an outside chance that once the structures are firmly elucidated that the isomer stated to be produced by Example 4 will actually be that produced by Examples 1-3, and vice versa.

(B) PREPARATION OF THE FUNGICIDAL COMPOSITIONS

Example 5

Sprayable powder: Percent

5 - acetylthio - methylthio - 3 - methylthio - 4 - cyano-isothiazole (or the corresponding 3-, 5- isomer thereof) -----	75
Sulfite waste liquor powder -----	15
Na-isobutyl-naphthalene sulfonate -----	1
White bole -----	9

The above components are ground together. The thus-produced powder is sprayed or atomized in the form of a dilute aqueous suspension.

Example 6

Sprayable powder: Copper oxychloride -----	70
3 - benzoylthio - methylthio - 5 - methylthio - 4 - cyano-isothiazole (or the corresponding 5-, 3- isomer thereof) -----	10
Oleic acid-N-methyl-tauride -----	5
Chalk -----	15

The above substances are finely ground together. The thus-obtained powder can be diluted with water to form a suspension in the desired concentration. The suspension can be sprayed or atomized.

Example 7

15 Dusting composition: Percent	
3 - acetylthio - methylthio - 5 - methylthio - 4 - cyano-isothiazole (or the corresponding 5-, 3- isomer thereof) -----	15
Powdered sulfur -----	25
Kaolin -----	15
Pyrophyllite -----	42
Colophonium -----	3

Example 8

25 Sprayable powder: Percent	
5-acetylthio - methylthio - 3 - ethylthio-4-cyano-isothiazole (or the corresponding 3-, 5-isomer thereof) -----	10
N-trichloromethylthio-phthalimide -----	40
Sulfite waste liquor powder -----	15
Na-isobutyl-naphthalene sulfonate -----	2
Chalk -----	33

The preceding examples can be repeated with similar success by substituting the generically and specifically described reactants and operating conditions of this invention for those used in the preceding examples.

From the foregoing description, one skilled in the art can easily ascertain the essential characteristics of this invention, and without departing from the spirit and scope thereof, can make various changes and modifications of the invention to adapt it to various usages and conditions.

What is claimed is:

1. A compound selected from the group consisting of

55 wherein

R₁ represents alkylene of 1-4 carbon atoms;

R₂ represents alkyl of 1-4 carbon atoms, or X_n-phenyl where n is an integer of 1-3 and X is hydrogen, hydroxyl, alkyl of 1-4 carbon atoms, or halogen, or 2X represents methylenedioxy; and

R₃ represents alkyl of 1-4 carbon atoms.

2. A compound as defined by claim 1 wherein the compound is represented by Formula Ia.

3. A compound as defined by claim 1 wherein the compound is represented by Formula Ib.

4. A compound as defined by claim 1 wherein the compound is 3-acetylthiomethylthio - 5 - methylthio-4-cyano-isothiazole.

5. A compound as defined by claim 1 wherein the compound is 5-acetylthiomethylthio - 3 - methylthio-4-cyano-isothiazole.

6. A compound as defined by claim 1 wherein the compound is 3-benzoylthiomethylthio - 5 - methylthio-4-cyano-isothiazole.

75 7. A compound as defined by claim 1 wherein the

3,481,946

9

compound is 5-benzoylthiomethylthio - 3 - methylthio-4-
cyano-isothiazole.
